CANE CAR

Alfred C. Schmohl, Beaver Falls, Pa., assignor to
 Pressed Steel Car Company, Inc., Pittsburgh,
 Pa., a corporation of Pennsylvania

Application September 21, 1938, Serial No. 230,904

2 Claims. (Cl. 105—367)

This invention pertains generally to cane cars of the type provided with movable side walls to facilitate discharge of lading and pertains specifically to means for releasably securing the said side wall in lading retaining position.

Cane cars of the type to which the present invention pertains are constructed to transport loads of cane from field to mill. Such cars when fully loaded carry from one to five or more tons of cane. The car side walls in the present invention are constructed of a longitudinal top member which is flexible and a plurality of depending flexible members spaced longitudinally of the top member, connected thereto and to the car underframe. These side walls are maintained in lading retaining position by connecting the ends of the longitudinal member to end walls or corner posts of the car and are moved to lading unloading position by disconnecting one or both ends of the longitudinal member and letting it fall to the ground. Obviously, the cane stalks in the car impose considerable tension in the longitudinal and depending flexible members, necessitating relieving of such tension to release the longitudinal member from the car end walls when ordinary means are used to connect the longitudinal member to the car end walls. Where the fastening means used are such as to require the operator to stand in the way of discharging cane when the side wall is dropped, there is danger of his becoming injured through contact with the cane lading or being struck by the longitudinal member.

An object of the present invention is to provide fastening means which may be operated from an end of the car without danger to the operator from being entangled with the side wall or lading.

A further object of the invention is to provide a fastening means which is readily releasable and yet protected against accidental release through pressure of lading or movement of car.

In the drawing forming part of this specification wherein Fig. 1 shows in side elevation a cane car equipped with the invention; Fig. 2 shows an enlarged end elevation of the invention and Figs. 3 and 4 show enlarged side elevation and plan views of the invention; reference character 1 indicates a conventional cane car underframe having end walls comprising corner posts 2 at each corner of the underframe and connected thereto by gusset plates 5. The tops of said posts 2 are joined by end members 3 and gusset plates 4.

The car side walls comprise a top longitudinal

flexible member such as a chain 6 and longitudinally spaced depending flexible members such as chains 7 for connecting the longitudinal member 6 to the underframe 1. Each end of chain 6 is preferably provided with a closed link 8 by means of which the fastening means of the invention connects the longitudinal member 6 with corner posts 2 to retain the side wall in lading retaining position.

10 Each fastening means comprises a hasp pivoted to the corner post and engaging the end link 8 of chain 6. A hasp lock is also pivoted to the post and engages the hasp to retain same in engagement with said link. The stress imposed on chain 6 by the lading or the weight of the chain alone will rotate the hasp into a position in which the chain end link 8 will fall from off the hasp unless the hasp is restrained from rotation. The hasp lock furnishes this restraint. Both hasp and lock have been designed to provide for positive engagement therebetween and when so engaged the action of the chain upon the hasp cannot effect separation of hasp and lock. Whenever it is desired to separate hasp and lock 15 the operator must rotate the lock away from the chain and hasp, which may be done with a minimum of effort and maximum of safety for the operator.

20 Each hasp comprises an eye 9 for pivotally engaging shaft 10 secured to post 2. Depending from said eye 9 is shank 11, the free end of which is deflected to one side of shaft 10 and away from chain link 8 to provide a link engaging portion and terminates in an end portion 12 for engagement with the hasp lock. This end portion 12 of shank 11 is preferably deflected downwardly for effecting a purpose hereinafter described.

25 Each hasp lock comprises a portion such as handle 13 to be grasped by the operator in manipulating the lock. At one end of handle 13 is a suitably formed portion to be engaged by shank 11 of the hasp and is illustrated in the form of spaced arms 14 between which the shank 11 extends. These arms 14 are connected together and to handle 13 to provide a portion to be engaged by shank 11 and its end portion 12. Each arm 14 terminates in an eye 15 pivotally mounted 30 on shaft 16 secured to the car end at post 2. To insure against accidental operation of the lock, as by striking an obstruction during movement of the car or during loading of lading, an angle shaped member 17 is secured to the corner post 2 and in the path of movement of the lock handle 35

13 when being rotated upon shaft 16 to effect separation of hasp shank 11 and the lock.

Referring now to Fig. 3 of the drawing wherein the hasp and lock are shown by full lines in a position to secure the chain 6 to post 2 it is apparent that any stress exerted by chain 6 upon shank 11 of the hasp will tend to rotate said shank towards the chain and dispose the shank in a substantially vertical position, permitting chain 6 and its link 8 to move off the said shank and release the chain from post 2. However, when shank 11 of the hasp is disposed between arms 14 of the hasp lock and end portion 12 of the shank engages the hasp lock any tendency toward rotation of the hasp from a force exerted through chain 6 will also rotate the hasp lock in the same direction, thereby preventing separation of hasp and lock and consequential release of chain 6 from post 2. Likewise, any rotation of the hasp lock towards the hasp or chain merely moves the hasp lock arms 14 along shank 11 towards the chain, as indicated by dot-and-dash lines, and does not release the hasp for rotation with consequential release of chain 6 from post 2. If handle 13 of the hasp lock is struck a blow tending to cause rotation of the lock in a direction away from the hasp and chain, the member 17 being disposed in the path of said movement of handle 13 prevents such rotation.

When, however, intentional separation is desired the operator grasps handle 13 and rotates it to the right of Fig. 3 which is towards the hasp and chain, as indicated by dot-and-dash lines, until the handle 13 clears member 17. The operator can then pull handle 17 outwardly away from post 2 until the handle 13 is in position for rotation to the left and away from hasp and chain as indicated by dot-and-dash lines to the left of post 2 on Fig. 3. In this latter position the hasp, being free of the lock, will rotate into a position in which link 8 of chain 6 can move off shank 11 of the hasp and permit that end of chain 6 to fall to the ground. By so manipulating the hasp lock at both ends of chain 6 the entire side wall of the car can be lowered.

Whenever it is desired to again erect the car side wall the operator grasps one end of chain 6, bringing link 8 thereof into position to engage hasp shank 11, moves the link over end 12 of the shank and again engages the hasp shank 11 with

the hasp lock as shown in Fig. 1 and by full lines on Fig. 3. By repeating this at each end of chain 6 the car side wall is erected into lading retaining position.

Having thus described the invention what I claim as new and desire to secure by Letters Patent is:

1. A collapsible lading body side wall of the character described comprising, a flexible longitudinal side wall member having apertured end portions for connection with side wall supporting members, a latch pivoted to each said supporting member for engagement with the adjacent apertured end portion of said longitudinal member, a latch lock pivoted to each said supporting member for movement into engagement with the adjacent latch to retain same in engagement with said longitudinal members and means on each said supporting member for selective engagement with said latch lock for preventing movement of said latch lock out of engagement with said latch.

2. In a car side wall structure including upwardly extending posts at each end of the side wall and a chain member connecting the upper ends of said posts; the connection between one end of the chain and the adjacent post comprising a latch member having an eye portion pivotally mounted on said post, a chain bearing portion depending from said eye portion and terminating in a latch lock engaging portion extending outwardly from said chain bearing portion; a latch lock comprising a bifurcated body portion, one end of which terminates in an eye portion pivotally supported on said post in spaced relation to said latch eye portion, the opposite end of said body portion terminating in a bearing for the outwardly extending portion of said latch and an elongated handle portion depending from said bifurcated body portion; a stop secured to said post and disposed in the path of said handle for normally preventing sufficient rotation of the handle to produce separation of the latch from its bearing on said bifurcated portion of the latch lock, said latch lock being movable a sufficient distance relative to said stop to free the latch lock for rotation and separation of latch and lock to free the chain from the said post.
